(57) **CLAIM**

The ornamental design for a vehicle wheel, as shown and described.

DESCRIPTION

FIG. 1 is a front view of a vehicle wheel constructed according to my novel design;

FIG. 2 is a right side view thereof; and,

FIG. 3 is a front right perspective view thereof.

A left side view has been omitted because this view is identical to the right side view shown in FIG. 2.

1 Claim, 3 Drawing Sheets

FIG. 1

FIG. 2

FIG. 3
